LATCH FOR PANELS

Oscar B. Pulis, Beaver Falls, Pa.

Application January 23, 1934, Serial No. 707,913

7 Claims. (Cl. 25—131)

This invention consists in a latch for securing two slotted plates in face-to-face contact, and finds practical application in securing together the panels of which the forms used in concrete building are made up. In that particular application it will be described.

In the accompanying drawings Fig. I is a view in outer elevation of a portion of such a form for concrete building. The form is made up of a plurality of panels, and the panels are united by the latch of this invention. Figs. Ia and Ib, associated with Fig. I, are views of the structure in plan from above and in end elevation. Fig. II is a view to larger scale, showing the latch in front elevation with its parts in such relative positions as they occupy when the latch is effective. The position of the panel that carries the latch is indicated in dotted lines. Fig. III is a fragmentary view in vertical section through the flanges of two assembled panels and showing in side elevation the latch in effective position. Fig. IV is a fragmentary view in elevation of the panel assembly and showing in front elevation the latch in release position. Fig. V is a view, otherwise corresponding to Fig. III, but showing the latch in release position.

The panels of which a form for concrete work is composed consist of flanged plates of steel; and the requisites of a successful latch are (1) that it secure the panels in accurate alignment, with their faces extending in a common plane; (2) that it be easy of operation; (3) that it be simple in structure; (4) that it be durable; and (5) that it be inexpensive. These requisites the latch of this invention possesses.

Referring, first, to Fig. I, the form is seen to be composed of a plurality of panels 1. Four of these panels here are shown. Though unequal in size (two of the four are of double the length of the other two) all are rectangular. Each consists of a plate with marginal flanges 2; and, as here shown, the panel structure is built by welding rolled angles along the edges of the separately rolled plates. Additionally, the panels may be reenforced with intermediately spaced angles 3 welded upon the plates. In the assembly the marginal flanges 2 of adjacent panels are brought to face-to-face abutment. The latch of the invention engages the abutting flanges. The flanges 2 are slotted, as at 4; and the slots are carefully proportioned and accurately positioned. In the assembly the slots of the abutting flanges come to registry with one another. Ordinarily each flange of each panel will be provided with two of the slots 4; or, if the panel be a long one, the flanges of its longer sides may be provided with a larger number of such slots. In the case illustrated in Fig. I, in which the larger panels are in length multiples of the smaller, the number of slots in the long flanges of the larger panels is

double that of the smaller panels, but the spacing of the succession of slots is uniform throughout,—this with the manifest purpose of permitting assembly of large and small panels in a variety of ways, as circumstances of use may require. Adjacent alternate slots each panel carries a plurality of latches 5.

Turning to Figs. II—V, each latch will be seen to consist essentially of a hook, to which in these figures the numeral 5 is immediately applied. The hook is mounted upon the panel, and conveniently upon that web of the marginal angle that is welded to the plate; and its mounting is such that it has two ranges of movement,—one pivotal with respect to its support, and the other in right-line direction. With this line of direction, as presently will more fully appear, the plane of the inner face of the hook is coincident. Such plurality of movements is effected by pivotal connection between the supporting panel and the supported hook, the connection including an elongate pivot hole. Conveniently, the elongate pivot hole is formed, as shown in the drawings at 51, in the body of the hook itself. The shank of the pivot pin 6 extends through this elongate pivot hole and into the substance of the panel itself, and the assembly is such that the hook can be swung pivotally or shifted longitudinally of the elongate hole, and manifestly the movement of the hook may be the resultant of the two particular movements specified, made simultaneously effective. Comparing Fig. V with Fig. III, it will be perceived that, when the hook is shifted to one end of its range of right-line movement, it may be swung pivotally to and from a position of transverse extension through the aligned slots 4, 4; and that, when it has been swung pivotally to such position through the slots, it may by right-line shift in a direction coincident with the extent of the slotted plates be brought to latching position upon the two panels at one end of the aligned slots. This latching position of the hook is the position shown in Fig. III.

The hook advantageously possesses certain characteristics of shape. It is notched and, by virtue of such notching, is of hook shape. The inner face 52 of the notch is plane, and when the hook is in latching position this face extends in a plane substantially coincident with the adjacent face of flange 2. The opposite outer face 53 of the notch flares outwardly. The bottom 54 of the notch extends in a plane perpendicular to the plane of the inner face 52, and it is of a width corresponding to the thickness of the two assembled flanges 2, 2. The flare of the outer face 53 is reduced at the bottom of the notch, so that at that point the opposite faces 52 and 53 are substantially parallel. These features of minute shape are such as to facilitate latching and unlatching, and at the same time such that as

the hook comes to latching position it draws the flanges firmly and holds them snugly together.

Cooperating with the hook is a wedge 7, of such shape and size that, when the hook has come to the latching position of Fig. III, it may be advanced in a position of transverse extension within the aligned slots 4, 4, and, engaging by its opposite and relatively inclined edges the hook on one side and the opposite end of the aligned slots on the other, it becomes a lock, to hold the hook from unlatching.

To serve such purposes the wedge and the associated parts are most carefully shaped. It will be observed of the wedge-engaging surface 15 55 of the notch of the hook that, when the hook is in latching position (Fig. III), this surface is oblique in its extent; and that, accordingly, the outer edge 71 of the wedge 7 extends in a plane that is coincident with the plane in which the edges of the slots 4, 4 are disposed. Thus the wedge is of maximum effect, the alignment of the panels perfected, and the structure carefully adapted to endure with effect throughout long periods of service.

25 Conveniently the wedge is carried in a slideway or casing 56 formed integrally with the body of the hook, and in that casing it may be made captive (while free to function in the manner described) by means of the slot and pin connection 57, 77 shown in the drawings. The forward end of the wedge is more steeply tapered, at 72, to allow free pivotal swing of the hook consequent upon a minimum range of withdrawal of the wedge. The rear end of the wedge is bent aside 30 at 73, to give purchase for a claw or other hooked tool, in withdrawing the wedge.

The inner face of the hook at its edges may be rounded, as indicated at 58, to facilitate pivotal swinging.

40 The assembled panels constitute a facing against which concrete may be shaped, and this facing is brought accurately to position, supported and braced by such means as the art knows.

45 The invention, manifestly, is of general applicability in the securing of plates in face-to-face positions. Additionally, if the parts be considered in the positions shown in Fig. V, it will be perceived that, by virtue of this, its more steeply tapered forward end, the wedge 7 may serve as the instrumentality for swinging the hook 5 to latched position. To accomplish this, it is necessary only to drive the wedge forward. Engagement of surface 72 upon the end of the slot 4 will effect this swing.

I claim as my invention:

1. A latch for securing two plates with slotted, bent-aside flanges in flange-to-flange contact, the latch consisting of a hook pivotally mounted upon one of the two plates and by such pivotal mounting adapted to swing to and from a position of transverse extension through the aligned slots of the two flanges, the said hook, in addition to such pivotal movability, being movable in its mounting in right-line direction and in a direction coincident with the extent of such plates, whereby, when swung to such position of transverse extension through the aligned slots of the two flanges, it may be advanced and retracted to and from a position of latching engagement with the two flanges at one end of the aligned slots, to-

gether with means for securing the hook in its advanced and locking position.

2. A latch for securing two slotted plates in face-to-face contact, the latch consisting of a hook pivotally mounted upon one of the two plates and by such pivotal mounting adapted to swing to and from a position of transverse extension through the aligned slots of the two plates, the said hook, in addition to such pivotal movability, being movable in its mounting in right-line direction, whereby, when swung to such position of transverse extension through the aligned slots of the two plates, it may be advanced and retracted to and from a position of latching engagement with the two plates at one end of the aligned slots, and a wedge adapted to be advanced in transverse extension through the so aligned slots of the two plates and, engaging simultaneously the seated hook and the opposite ends of the aligned slots, to secure the hook in its advanced and locking position.

3. A latch for securing two plates with slotted, bent-aside flanges in flange-to-flange contacts, the latch consisting of a hook pivotally mounted through a slotted pivot hole upon one of the two plates and by such mounting adapted to swing to and from a position of transverse extension through the aligned slots of the two flanges and adapted further (when in such position of transverse extension) to be advanced and retracted in a direction coincident with the extent of such plates to and from latching engagement with the two flanges at one end of the aligned slots, together with means for securing the hook in its advanced and locking position.

4. A latch for securing two slotted plates in face-to-face contact, the latch consisting of a notched hook pivotally mounted upon one of the two plates and by such pivotal mounting adapted to swing to and from a position of transverse extension through the aligned slots of the two plates, the said hook, in addition to such pivotal movability, being movable in its mounting in right-line direction, whereby, when swung to such position of transverse extension through the aligned slots of the two plates, it may be advanced and retracted to and from a position of latching engagement with the two plates at one end of the aligned slots, the outer face of the notch of the hook flaring outwardly with respect to the inner, and the inner face of the notch of the hook being plane-surfaced and (when the hook is pivotally swung to its position of transverse extension through the aligned slots) extending in substantially coincident plane with the adjacent plate surface.

5. The structure of claim 2, the wedge being carried in a slideway formed integrally with the hook.

6. The structure of claim 2, the wedge being carried in a slideway formed integrally with the hook and being connected by pin-and-slot connection with such slideway.

7. The structure of claim 2, the wedge-engaging surface of the hook extending, when the hook is in locking position, in a plane oblique to the horizontal, whereby the advancing wedge makes simultaneous engagement in horizontal plane with the edges of the slots of the two plates.
